J. C. Strode,

Water Wheel.

Patented Feb. 8, 1831.

Joseph L. Stander
1900-1901

6368 11 X

The following expression from the Honorable Tolson was made in part of the
same speech, in which he spoke of the conduct of General Joseph L. Radford,
himself, of his own personal conduct in his office, for not fulfilling his duty & other
military officers called upon. Radford took no stand.

and some more in the larger and more upright positions. The upper
shoulder is placed so that the shoulder of the man is of the same height as the
shaft will be in its final construction. The arms are made of wood and
means of a lever with a door pull compensated by figure 11 being the lever
on which the door pull is made is not so much than the opposite side
& the middle on the shaft is of the same shape so that when the upper is turned
on the side opposite to the door pull it will be turned together on all sides.

(3-300 12)

is the distance from the top of the nail head to going up
of the staff, and the distance from the top of the going up to the
point of the nail head. In the going up position will
give the dimensions of a machine made in position from settings down
will give a lever of twenty feet. If a larger or smaller wheel is required,
the dimensions of the several parts will vary according to the proportions
given. One additional point may be taken by the application of a
funnel to each of the holes in the ends of the arms 2, 2, 2, 2, 2, 2, the small
end of the funnel being applied to the hole and the wide end standing
outwards. These funnels may be made of small blocks of wood with a
hole bored thru them made of each and hollowed on the inferior side
so as to fit the arms to which they may be attached firmly by nails or
screws. The holes in the blocks should expand in capacity expansion
on the inferior side with the holes in the arms and should gradually widen
toward the line from the top to the bottom surface of the blocks. These
funnels may or may not be attached at the option of the inventor. The
machine will move very well without them, though it is believed from
experience that a more noise appears with them. If a reciprocating
movement is desired it may be obtained by means of a crank on the angle
of the staff and in the machine above described the crank is at the end
of the angle but of course a little further to make to work on a point fix-
ed in a permanent block placed directly opposite the smaller extremity
of the staff. If the intermediate space between the end of the staff & the block
is sufficient to form a crank by which the reciprocating movement
may be given. There will be less friction & consequently a gain of power.
I declare that the above is a true specification of my said invention
and that all the above parts belong to me and shall this twenty fifth day of
January in the year of our Lord one thousand eight hundred & thirty one
